CERTIFICATE OF CORRECTION

PATENT NO. : Des. 494,984 S
DATED : August 24, 2004
INVENTOR(S) : Katja Peter et al.

Page 1 of 1

It is certified that error appears in the above-identified patent and that said Letters Patent is hereby corrected as shown below:

Title page,

Item [54], Title, delete “**COMPUTER ICON FOR TRANSMITTED LIGHT ILLUMINATION FUNCTIONS OF A MICROSCOPE SYSTEM ON A PORTION ON A DISPLAY PANEL OR MICROSCOPE DISPLAY**” add
-- **IDEOGRAM FOR TRANSMITTED LIGHT ILLUMINATION FUNCTIONS OF A MICROSCOPE SYSTEM ON A PORTION OF A DISPLAY PANEL OR MICROSCOPE DISPLAY --**

Item [57], **CLAIM**, delete “The ornamental design for a computer icon for transmitted light illumination functions of a microscope system on a portion of a display panel or microscope display, as shown and described.” add
-- The ornamental design for an ideogram for transmitted light illumination functions of a microscope system on a portion of a display panel or microscope display as shown and described. --

Signed and Sealed this

Fourteenth Day of December, 2004

JON W. DUDAS
Director of the United States Patent and Trademark Office
